UNITED STATES PATENT OFFICE.

JAMES R. CLARK, OF WATSON, NEW YORK.

SAND-BAND FOR VEHICLES.

SPECIFICATION forming part of Letters Patent No. 340,286, dated April 20, 1886.

Application filed January 11, 1886. Serial No. 188,224. (No model.)

To all whom it may concern:

Be it known that I, JAMES R. CLARK, a citizen of the United States, residing at Watson, in the county of Lewis and State of New York, have invented certain new and useful Improvements in Sand-Bands for Vehicle-Wheels; and I do hereby declare the following to be a full, clear, and exact description of the invention, such as will enable others skilled in the art to which it appertains to make and use the same, reference being had to the accompanying drawings and letters of reference marked thereon, which form a part of this specification.

Like letters refer to similar parts throughout the several views.

My invention relates to sand-bands for vehicle-wheels; and it consists in the peculiar construction and adaptation of the band or guard, as will be more fully hereinafter described, and particularly pointed out in the claim.

In the accompanying drawings, Figure 1 is a side elevation of a vehicle-hub with a portion of the axle, showing the sand-band applied. Fig. 2 is a transverse section through the axle on the line xx of Fig. 1. Fig. 3 is a perspective view of the sand-band detached.

Referring to the drawings, A represents a sand-band, made, preferably, of sheet metal.

B is a disk, having a portion of its lower side cut away, as shown at a . The disk B is provided at its periphery with an outwardly-projecting flange, C, adapted to fit over the inner end of the hub D of the wheel and prevent sand or other material from entering the interior of the wheel. The flange C is cut away upon its lower side, coincident with the cut-away portion of the disk, thus forming the opening a' beneath the hub, which will permit any grease, tar, or other lubricating material escaping from the interior of the wheel to fall to the ground. The advantage of this feature will be readily understood.

If, instead of the opening a' , the flange C were extended entirely around the hub, the drippings from the axle-tree would in a meas-

ure be retained and accumulate between it and the hub.

The opening E is formed in the center of 50 the disk B of such form and size as to conform to the axle-tree of the vehicle upon which the band is to be used.

F is a shank or extension formed integral with the inner face of the disk B. It is of 55 such form as to permit it to fit over and embrace the end of the axle-tree. The shank F is open upon its lower side, the opening being coincident with the opening a in the disk, and consequently with the opening in the flange C. 60

G is an ordinary carriage-clip, which is fitted over the shank F, and serves to hold the same securely in place, and yet allow of its being easily and quickly removed when desired.

I am aware of Patents Nos. 204,719 and 65 220,458, and make no claim to the construction shown therein as forming a part of my invention.

I am also aware of the Patents Nos. 123,582 and 150,362, and do not seek to cover such 70 construction in this application. Neither do I claim a dust-band hinged to the axle, but limit myself to the construction herein shown and described.

Having thus described my invention and 75 set forth its merits, what I claim to be new, and desire to secure by Letters Patent, is—

The improved sand-band described, comprising in a single element the disk B, outwardly-projecting flange C, and the shank F, 80 in the form of a rectangular box with one side removed, the said disk being cut away coincident with the open side of the shank, as at a , and the flange cut away coincident with the cut-away portion of the said disk, as at a' , substantially as shown, and for the purpose specified.

In testimony whereof I affix my signature in presence of two witnesses.

JAMES R. CLARK.

Witnesses:

C. S. MERENESS,
HORACE BUSH.
